GARMENT SUPPORT

Anna J. Fishbone, New York, N. Y.

Application February 7, 1934, Serial No. 710,152

1 Claim. (Cl. 241—1)

This invention relates to garments and more particularly to a combination body embracing device and garter support.

One of the objects of the invention is to provide a body shaping device such as a corset, corselet or the like and provided with garters to support the stockings of the wearer in place, the garters at the same time acting as an anchoring means to prevent the body shaping device from creeping upwardly on the body of the wearer.

Another object of the invention is to have the anchoring means in the form of elastic bands or garters encircling the legs or thighs of the wearer and supported by vertically disposed straps attached at their upper ends to the body of the garment and provided with means to adjust the relative distance between the body portion of the garment and the garters.

Other objects of the invention will appear as the disclosure progresses. The drawing is intended to merely indicate a possible embodiment of the invention. It is obvious that the actual needs of manufacture may necessitate certain mechanical changes. It is therefore not intended to limit the invention to the embodiment illustrated but rather to define such limits in the appended claim.

In the embodiment illustrated Figure 1 is a view showing the front member of the belt portion of the garment, the limb encircling members and the associate parts connecting the leg encircling members to the belt portion.

Figure 2 is a section or line 2—2 of Figure 1. Figure 3 is a top view of the garment with the garters omitted.

Referring to the figures in detail numeral 1 designates the belt portion of the garment which is adapted to fit snugly around the hips of the wearer, 2 the straps made of resilient material and supported from the belt, and 3 the adjusting non-elastic imperforate strips for supporting the limb encircling members 4 made of elastic material. The belt portion 1 comprises front and back members 5 and 6 of equal shape and size and made of non-elastic material and side inserts 7 and 8 made of elastic material. As noted

in Figure 3 the ends 9 and 10 are joined together by snap fasteners 11 in order to provide means to open and close the garment around the body of the wearer.

The upper ends of the straps 2 are attached to the belt portion 1 and to the lower ends of the straps are anchored metallic loops 12. Numeral 13 designates flexible non-elastic strips supported at the upper ends by the loops 12, and fastened at the lower ends thereof are buttons 14. These buttons pass through the narrowed lower ends of the loops and are adapted to cooperate with the said loops for gripping the adjusting strips 3 as best seen in Figure 2. By such means the relative position of the belt 1 and the garters 4 can be regulated and adjusted in the well-known manner to suit the needs of the wearer.

Having described my invention, I claim

In a garment of the class described, a belt portion, two pairs of elastic straps sewed at their upper ends to said belt portion, the bottom ends of said elastic straps having metallic loops permanently attached thereto, flexible non-elastic strips provided with buttons at their lower ends and suspended at their upper ends from said metallic loops, limb encircling members comprising elastic circular body portions, means to adjust the distance between the said belt portion and said limb encircling members, said means being adjacent to said limb encircling members and including non-elastic imperforate adjusting strips, the lower ends of said non-elastic adjusting strips being directly and permanently attached to said elastic body portions of said limb encircling members, the upper ends of said non-elastic imperforate strips adapted to be adjustably gripped between the said buttons and said loops so that the distance between the body portion of the garment and said limb encircling members can be regulated in an indefinite amount within the limits of said adjusting strips, the free and loose ends of said adjusting strips pointing upwardly so they can readily be gripped.

ANNA J. FISHBONE.
